UNITED STATES PATENT OFFICE.

FRANK E. PARR, OF BUFFALO, NEW YORK.

SAW-VISE.

1,313,728.

Specification of Letters Patent.

Patented Aug. 19, 1919.

Application filed December 15, 1917. Serial No. 207,371.

To all whom it may concern:

Be it known that I, FRANK E. PARR, a citizen of the United States, residing at Buffalo, in the county of Erie and State of New York, have invented a new and useful Improvement in Saw-Vises, of which the following is a specification.

This invention relates to vises for holding saws or other flat articles while the same are being sharpened or otherwise operated upon.

In vises of this kind, as heretofore made, the arch members connecting the fixed and movable jaws were either so arranged that the saw could be inserted between the jaws from below the vise, or the connecting members were so arranged that the saw could be inserted between the jaws only from above the vise. In sharpening and jointing saws it is very desirable to have a vise in which the saw can be inserted between the jaws either from above or from below the vise.

The objects of the invention are to produce a vise of this kind in which the member connecting the fixed and movable jaws is so constructed and arranged that the saw may be inserted between the jaws either from above or from below the jaws; also to improve the construction of vises of this kind in other respects hereinafter specified.

In the accompanying drawings:—

Figure 1 is a front elevation of a vise embodying the invention showing the connecting members in a position to receive a saw between the jaws from below the vise.

Fig. 2 is a similar view thereof showing the parts in different positions so that the saw may be inserted into the vise from above the same.

Fig. 3 is a transverse sectional elevation thereof on an enlarged scale on line 3—3,

Fig. 1.

Fig. 4 is a transverse sectional elevation thereof on line 4—4, Fig. 1.

Figs. 5 and 6 are transverse sectional elevations thereof on lines 5—5, and 6—6, respectively, Fig. 2.

Fig. 7 is a top plan view thereof, partly in section.

The vise embodying the invention which is shown in drawings has a fixed jaw A which is adapted to be secured to a table, bench or other support, the jaw shown being angle-shaped and having a table or bench-engaging member or bracket a secured

thereto. The fixed jaw may be secured to a table or bench a' by any suitable means, such as a clamp a² pivoted at a³ to the fixed jaw and being provided with a clamping screw a⁴ adapted to engage the lower face of the table or support and to clamp the vise thereon. The movable jaw of the vise includes a plate or member B arranged in operative relation to the vertical face of the fixed jaw member A. The movable jaw is slidable on blocks or guide members C which are fixed relatively to the jaw A and which are preferably arranged near the ends of the movable jaw B. In order to guide the movable jaw relatively to the fixed jaw, the ends b of the movable jaw, in the construction shown, are bent into a position substantially perpendicular to the face of the movable jaw and are provided with flanged portions b' b'', the bent portions b and the flanged portions thereof slidably engaging three sides of the guide blocks C. The movable jaw may be actuated by any suitable means, that shown including a rod D having eccentrically arranged pivots or pintles d journaled in the guide blocks or members C and provided with a handle d' for turning the rod D about its pivots. The rod D is arranged parallel to the movable jaw B and engages the same for moving the jaw toward the fixed jaw and also acts as a reinforcement or support for the movable jaw. The actuating rod D and the movable jaw are preferably connected intermediate of their ends by any suitable means, such as a bent rod or strap d' which embraces the eccentric rod D and causes the movable jaw to be withdrawn from the fixed jaw when the eccentric rod is turned in a direction to release the saw. E represents a saw to be sharpened. The fixed and movable jaws and the guide members and actuating members for the movable jaw, of themselves constitute no part of this invention and may be of any suitable or desired construction.

The movable jaw is supported from the fixed jaw by means of connecting or arch members F, which, in the construction shown, are substantially U-shape and each of which is pivoted at one end to the vertical flange of the fixed jaw A and at its outer end to the guide member C. The arch or connecting members are arranged at the ends of the jaws, parts of the horizontal flange of the fixed jaw being cut away so

that the members can be swung about their pivots to either the upper positions shown in Fig. 1, in which a saw or other device can be inserted between the jaws from below the vise, or the connecting members may be swung into their lower positions so as to enable a saw to be inserted between the jaws from above the vise, as shown in Fig. 2. Any suitable means may be provided for pivoting the connecting members F to the fixed jaw and the guide blocks or members. In the construction shown the connecting members F are pivoted on bushings f extending through holes in the connecting members and secured to the fixed jaw and to the guide members by means of screws f' or the like.

By means of this construction, the movable jaw is securely held with regard to the fixed jaw, and the connecting members can be easily shifted from one position to another to permit the saw to be inserted into the vise as shown in Fig. 1, in which the saw is securely held or gripped in close proximity to the teeth so that the teeth thereof can be filed or set as may be desired, or the saw may be held in the vise, as shown in Fig. 2, in such a way as to expose the entire saw edge for running a tool along the teeth of the saw for jointing the saw. The connecting members thus readily adapt the vise to hold the saw in either manner and avoid the necessity of reversing the vise on the table or support as has heretofore been necessary.

I claim as my invention:—

1. In a vise, the combination with a fixed jaw and a movable jaw, means for securing said fixed jaw to a support, and means for pressing said movable jaw toward said fixed jaw, of members movably connected to said fixed jaw and to said movable jaw and adapted to be positioned either above or below said jaws without changing the position of said jaws to permit an article to be inserted between the jaws of the vise either from above or below the vise without detaching said vise from said support.

2. In a vise, the combination with a fixed jaw and a movable jaw spaced apart to

form a slot to receive the work, and means for pressing said movable jaw toward said fixed jaw, of connecting members each of which has a pivotal connection with said fixed jaw and with said movable jaw and which may be swung into a position in which the slot between the jaws opens upwardly or into a position in which the slot opens downwardly.

3. In a vise, the combination with a fixed jaw and a movable jaw spaced apart to form a slot to receive the work, and means for pressing said movable jaw toward said fixed jaw, of a pair of substantially arch-shaped connecting members each of which has a pivotal connection with said fixed jaw and said movable jaw, said connecting members being arranged at the ends of said jaws and being adapted to swing either above or below said jaws for causing said jaws to open upwardly or downwardly.

4. In a vise, the combination with a fixed jaw and a movable jaw, of guide blocks on which said movable jaw is slidably, means engaging said guide blocks and said movable jaw for pressing said movable jaw toward said fixed jaw, and members connecting said guide blocks and said fixed jaw, said members being adapted to be positioned either above or below said jaws to permit an article to be inserted between said jaws either from above or from below the vise.

5. In a vise, the combination with a fixed jaw adapted to be secured to a support, and a movable jaw adjustable relatively to said fixed jaw for clamping an article between said jaws, a member connecting said fixed and movable jaws and movable into a position in which the slot between the jaws opens upwardly and into a position in which the slot between said jaws opens downwardly, said connecting member being movable from one position to another without disconnecting said vise from said support.

Witness my hand this 12th day of December, 1917.

FRANK E. PARR.
